UNITED STATES PATENT OFFICE.

ALEXANDRE LECLAIR, OF MONTREAL, QUEBEC, CANADA.

TRAIN-LINE COUPLING.

1,366,337.

Specification of Letters Patent. Patented Jan. 18, 1921.

Application filed June 14, 1919, Serial No. 304,332. Renewed December 2, 1920. Serial No. 427,846.

To all whom it may concern:

Be it known that I, ALEXANDRE LECLAIR, a subject of the King of Great Britain, and residing at 195 Delinelle street, in the city 5 and District of Montreal, in the Province of Quebec, in the Dominion of Canada, have invented a new and useful Train-Line Coupling, of which the following is a specification.

10 The invention relates to train line couplers as described in the present specification and illustrated in the accompanying drawings that form part of the same.

15 The invention consists essentially in the novel means employed, whereby the fluid passages are maintained in a direct line of flow at the joints between cars.

20 The objects of the invention are to avoid the dangers incident to coupling train lines by means of the customary hose connections; to insure better joints between cars; to save power by the elimination of elbows and other diverting elements in the line flow of fluid and incident to connecting the pipe 25 lines of one car to the pipe lines of the other cars; to reduce weight of parts necessary in such equipments; and generally to provide a simple, cheap, durable and efficient coupler for the fluid pipe lines.

30 In the drawings, Figure 1 is a longitudinal sectional view of the coupling device, showing also the draw bars and car couplers.

Fig. 2 is a front view of the casing without the coupling block, in order to disclose 35 the interior arrangements for the flexibility of the block.

Fig. 3 is a perspective detail of a coupling block.

40 Fig. 4 is a perspective detail of one of the carriages supporting the coupling block.

Like numerals of reference indicate corresponding parts in each figure.

Referring to the drawings, the block indicated by the numeral 1 is the coupling member at each end of a car and coacts with a similar member on the next car in making the joint.

50 The block 1 is formed with the vertical and curved tongues 2 and 3, one on one side and the other on the other side and, the flat face 4.

The fluid tube holes 5, 6 and 7 are arranged in a vertical row and extend through 55 the block and around these holes are recesses 8 in the face 4, each containing a washer 9,

which encircle the end of the flexible rubber tubes 10, 11 and 12.

The guiding pin 13 having a cone-shaped head 14 projects from the face 4 intermediate of the height thereof and to one side of the said fluid holes and at the other side a corresponding guide pin hole 15 is made in the face to receive the guide pin from the coupling block of the next car.

60 The split guiding flange 16 is secured to the block 1 and extends beyond the face 4 and is beveled on the inner side 17 for centering purposes, one half of said flange being secured to the coupling block of one car and the other to the meeting coupling block of 65 the next car.

70 The lugs 18 project outwardly from the back of the block and carry the pins 19 projecting above and below the lugs and this completes the coupling block and its attachments.

75 The carriage members 20 are each formed with a curved and vertical groove 21, in which the tongues 2 and 3 fit and slide, and the horizontal rail groove 22 across the back 80 centrally of the height.

85 The lugs 23 and 24 project outwardly from the face of each carriage member 20 at the top and bottom and have the pins 25 and 26 extending inwardly therefrom. Another pin 27 extends from the rear end of each carriage member intermediate of the height thereof and the spiral springs 28 encircle said pins 27.

90 The lugs 23 and 24 are in vertical alignment with the lugs 18 and the pins 25 and 26 with the pins 19 and the spiral springs 29 and 30 on each side balance the coupling block 1 between the lugs 23 and 24.

95 The casing 31 is formed with the horizontal rails 32 centrally of the height of the inner side walls, on which the carriages 20 slide in the grooves 22, and the pin holes 33 through the back for the pins 27, the springs 28 providing the required resiliency between the rear ends of the carriages 20 and the back wall of the casing 31.

100 The casing 31 is secured by the bracket 34 to the draw bar 35 and further braced by the struts 36 to said draw bar.

110 The draw bar 35 terminates the automatic coupler 37 as customary and which has nothing to do with this invention for any form of coupler may be used, but in the type illustrated or any other kind, the center line 38 of the coupler members of the car is in direct

line with a line through the meeting faces of the train line coupling blocks, but the same line from the regular coupling member, when the cars are separated is behind the face line of the coupling block 1 because the springs to the rear of the latter impel it forwardly, as soon as it is free from engagement with the coupling block of the next car.

In the operation of this invention, the cars 10 are brought together as usual and the automatic couplers engage in the well known fashion and this effectually locks the cars together until released. As the cars come together the guiding pins from the faces of 15 the coupling blocks of the train lines find the holes respectively in the meeting faces and slide in until centered. Simultaneously the split guide flanges meet the opposite block edges and contribute to the centering 20 in addition to their function of closing in efficiently the meeting faces forming the joint.

The vertical springs supporting the blocks from the carriages supply the adjustability 25 for cars of different height and as cars generally do not vary more than a few inches or less, it is very easy to take care of different standard designs of cars. The horizontal springs behind the carriages provide the 30 resiliency required to hold the meeting blocks together and to furnish the necessary flexibility to keep said faces together in rounding curves and during vibratory movement incident to the travel of railway cars.

35 There are no release measures required, as the coupling block faces simply meet and part without in any way interlocking.

The tube holes in the coupling block of the last car are plugged with any kind of 40 stopper threaded or otherwise, as it is obvious that they must be closed at the rear end and this forms no part of my invention.

45 Many changes may be made in the details of construction without departing from the spirit of the invention, and so long as they are within the scope of the claims for novelty following, the protection granted shall not be invalidated.

What I claim is:—

50 1. In a train line coupler, a coupling block

formed in the front face to meet an opposing and coacting block and having fluid passages therethrough and lugs from its back and pins from said lugs, a casing for said block, and carriage members having 55 upper and lower lugs and springs from said lugs cushioned against said lugs from the block and spring held to their forward position.

2. In a train line coupler, a coupling block 60 formed in the front face to meet a coacting block and center itself and having fluid passages and intermediate lugs from the back, carriage members slidably supporting said block and having top and bottom lugs in 65 alinement with the aforesaid lugs, the latter being spring held therebetween, springs mounted on pins attached to said carriage members and holding the latter to their forward position, and a casing having tracks 70 for said carriages and holes for said pins and rigidly supported from the draw bar.

3. In a train line coupler, a casing rigidly supported from the draw bar having side rails and pin holes in the back, a coupling 75 block having a front face formed to meet and center on a similar face on a coacting block and fluid passages therethrough, flexible tubes extending through said passages, resilient washers recessed in said face and 80 encircling said tubes, carriage members having a groove fitting to said rails across the back and vertical grooves in the face fitting to corresponding tongues from the coupling block, lugs from the top and bottom of said 85 carriage members having pins projecting therefrom, intermediate lugs from the coupling block having pins projecting therefrom, springs on said pins between said intermediate lugs and said top and bottom 90 lugs, pins secured to said carriage members and projecting rearwardly through the pin holes in said casing and encircling said rearwardly extending pins between the back wall of the casing and the rear end walls of 95 said carriage members.

Signed at the city of Montreal, Quebec, Canada, this 9th day of June, 1919.

ALEXANDRE LECLAIR.
